Primary Examiner—M. N. Pandozzi

[57] **CLAIM**

The ornamental design for a tangle-free flag pole accessory with coupleable rotatable top portion, as shown and described.

DESCRIPTION

FIG. 1 is a front elevational view of the tangle-free flag pole accessory with coupleable rotatable top portion showing my new design;

FIG. 2 is a rear elevational view thereof;

FIG. 3 is a right view thereof;

FIG. 4 is a left view thereof;

FIG. 5 is a top plan view thereof; and,

FIG. 6 is a bottom plan view thereof.

FIGS. 1-4 are drawn broken away to show indefinite length.
